(57) **CLAIM**

We claim the ornamental design for an electronic cigarette, as shown.

DESCRIPTION

FIG. 1 is a perspective view of an electronic cigarette according to an embodiment.

FIG. 2 is a front view of the electronic cigarette depicted in FIG. 1.

FIG. 3 is a back view of the electronic cigarette depicted in FIG. 1.

FIG. 4 is a right side view of the electronic cigarette depicted in FIG. 1.

FIG. 5 is a left side view of the electronic cigarette depicted in FIG. 1.

FIG. 6 is a top view of the electronic cigarette depicted in FIG. 1; and,

FIG. 7 is a bottom view of the electronic cigarette depicted in FIG. 1.

The broken lines in the drawings represent unclaimed environmental subject matter and form no part of the claim.

1 Claim, 3 Drawing Sheets
